UNITED STATES PATENT OFFICE.

JOHN HENRY FLORA, OF TUNNEL HILL, ILLINOIS.

PNEUMATIC TOY.

No. 847,755.

Specification of Letters Patent.

Patented March 19, 1907.

Application filed October 18, 1906. Serial No. 339,532.

To all whom it may concern:

Be it known that I, JOHN HENRY FLORA, a citizen of the United States, residing at Tunnel Hill, in the county of Johnson and State of Illinois, have invented certain new and useful Improvements in Pneumatic Toys, of which the following is a specification.

This invention has for its object to provide a toy for affording amusement, and which in practice will be adapted to leap or jump, the force being derived from the tendency of the toy to assume its normal shape after a portion has been deflected or pressed inward.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment is shown in the accompanying drawings, in which

Figure 1 is a side view of a toy embodying the invention, the dotted lines showing the position of the hand preliminary to pressing a part of the toy inward. Fig. 2 is a view similar to Fig. 1, showing a portion of the toy pressed inward. Fig. 3 shows the toy on the fly after being released. Fig. 4 is a modification. Fig. 5 is a view showing a part of the modified form of toy pressed inward. Fig. 6 is a view showing the modified form of toy on the fly.

Corresponding and like parts are referred to in the following description and indicated in all the views of the drawings by the same reference characters.

The toy may have any form—that is, it may represent any animal or the outline of the human figure. The toy is hollow and is constructed of rubber or like elastic or flexible material so as to admit of a portion being deflected or pressed inward, the confining walls yielding to accommodate the displaced air, and the part pressed inward being sub-

jected to tension, whereby upon release of the toy the same will leap or fly through the air, as indicated in Figs. 3 and 6. In the preferable construction the toy is formed of rubber sufficiently thin to yield slightly, yet retain the desired shape.

The toy is inflated and for this purpose is provided with a tube 1, through which the air is forced into the toy, the outer end of the tube being closed, preferably, by means of a string 3, wrapped about the same and tied, said string also serving as means to prevent loss of the toy and insure its return after leaping or moving on the fly. The toy is provided with a pouch or sack 4, which is adapted to be pressed inward against the outward pressure of the air, thereby increasing the inner pressure by the amount of air displaced, according to the degree of inward movement of the part 4. The sack, pouch, or part 4 is designed chiefly to cause the toy to leap or jump, and it may be properly designated as a "pneumatic rebounder."

When the toy is inflated, the hollow extension 4 is likewise distended, and when it is desired to produce a leaping or jumping effect the pneumatic rebounder is pressed inward and secured between the thumb and finger, as indicated most clearly in Fig. 2, and upon suddenly releasing the toy the part 4, quickly assuming a normal position, will cause the toy to leap or jump, as shown most clearly in Fig. 3.

In some shapes of the toy the sack or pouch 4 in the form indicated in Figs. 1, 2, and 3 may be omitted, as indicated in Figs. 4, 5, and 6, the shape of the toy admitting of a portion being pressed inward to form the pneumatic rebounder, as indicated in Fig. 5, the jumping effect being produced by suddenly releasing the toy after a part thereof corresponding to the pneumatic rebounder has been pressed inward.

Having thus described the invention, what is claimed as new is—

1. A pneumatic toy provided with a tube through which air is adapted to be forced into the toy when inflating the same, and a string for closing said tube and serving to ef-

feet a return of the toy after jumping, said toy having a portion thereof adapted to be pressed inward to form a pneumatic re-bounder and which when released causes the 5 toy to jump or fly through the air.

2. A pneumatic toy adapted to be inflated and provided with a sack or pouch adapted to be pressed inward to form a pneumatic re-bounder to produce a jumping or leaping ef-

fect when the toy is suddenly released after 10 said pneumatic sack has been pressed inward.

In testimony whereof I affix my signature in presence of two witnesses.

JOHN HENRY FLORA. [L. s.]
